UNITED STATES PATENT OFFICE

HENRY J. RIES, OF IOWA CITY, IOWA

COMB

Application filed July 17, 1929. Serial No. 378,976.

This invention relates to improvements in combs.

More particularly, the invention relates to improvements in combs of the type that may be carried in a pocket, pocketbook, or handbag of the user, or may be made the part of a toilet kit for traveling or the like.

An object of the invention is to provide a comb as above characterized that may be conveniently manipulated or folded to form a compact case of a durable character adapted to exclude dust and dirt.

It is also an object of the invention that the teeth forming the comb may be supported for separate pivotal movement and thereby enable the comb to be substantially self-cleaning.

A further object of the invention is that the case will serve as a means for gripping and rigidly holding the teeth when used as a comb.

Other objects of the invention relating to details of construction will appear in the detail description to follow.

The invention is illustrated by way of example in the accompanying drawing, in which:

Figure 1 is a perspective view of the comb when folded,

Figure 2 is a perspective view of the comb when unfolded and ready for use,

Figure 3 is a perspective view of the comb at a time when the case has been opened,

Figure 4 is a sectional view on line 4-4 of Figure 2, and

Figure 5 is a fragmentary detail view when looking at the teeth of the comb when unfolded or extended as in Figure 2.

Referring to the drawings more particularly 10 designates generally the supporting or bottom section of the comb case, and 11 the lid or top section therefor.

The bottom section of the case may be made of any suitable light and durable material and comprises an elongated rectangular plate with each end terminating in an upturned lip 12. The lid or top section 11 comprises an elongated rectangular plate with an edge portion suitably turned to form a

sleeve 13 adapted to fit between the sleeves 14 formed on the associated edge of the bottom section 10. A pintle pin or rod 15 is extended through the sleeves 13 and 14 and thereby providing a hinge for the sections 10 and 11.

The lid 11 fits between the lips 12. The lips 12 taper toward the hinged edge of the bottom section 10 as best shown in Figure 4, and the bottom section and lid are shaped in cross-section to correspond with the shape of lips 12 as shown. The free or front edge of the lid is formed with a downwardly extending lip 16 which is serrated as shown in Fig. 5 to provide teeth 17 for the purpose of which will later appear.

A rod or wire 18 is supported between the forward ends of the lips 12, said rod carrying a multiplicity of teeth 19. Each tooth comprises the usual shank portion tapering to a point at its outer end. The inner end of each tooth is formed with a head 20 which is pierced with an opening adapted for loosely receiving the rod 18. The teeth 19 are spaced by suitable washers 21. The teeth are free to swing upon the rod 18 and rest upon the bottom section 10 when not in use, or be swung to the position shown in Figures 2, 3 and 4 and rest upon an upturned lip 22 formed along the forward edge of the bottom section 10.

As shown in Figure 1, with the teeth 19 arranged to rest upon the bottom section 10, the lid 11 may be closed and its lip 16 seated upon the heads of the teeth 19. In this way a compact and artistic comb case is provided. Also the comb is kept free from dust and dirt.

When it is desired to use the comb it is only necessary to lift the lid 11 and permit the teeth 19 to swing outwardly to their extended position as shown in Figures 2, 3, and 4. When in their extended position the teeth rest upon the upturned lip or flange 22 and the lid is closed to bring its lip or flange 16 upon the teeth and allow its serrated edge 17 to engage the teeth for rigidly holding the same as shown in Figure 5.

When using the comb the case should be grasped between the thumb and forefinger

and this causes the teeth to be gripped between the lid and bottom sections of the case. In this manner the teeth are rigidly held as long as the user grips the case as described.

5 It should be noted that with the teeth free for individual swinging movement, it is made possible to cause self-cleaning thereof. This is due to the movement between the teeth when folding or unfolding the 10 same. This self-cleaning action is of value in keeping the comb free from dandruff and other foreign matter with which the teeth of a comb usually become clogged.

While I have shown and described the preferred form and construction of my invention, I wish it to be understood that I am aware of the fact that changes may be made in the general combination and arrangement of parts by those skilled in the art without departing from my invention as indicated by the appended claims.

I claim:

1. A comb comprising a case, and a multiplicity of separate and independent teeth 23 pivotally supported by the case and capable of being swung to an unseen position within the case and also capable of being swung to a position to extend from the case and serve to form a comb.

30 2. A comb comprising a case, a multiplicity of separate and independent teeth pivotally supported by the case and capable of being swung to an unseen position within the case and also capable of being swung to a position to extend from the case and form a comb, and cooperating means carried by the case whereby the teeth may be held rigidly in their extended position.

40 3. A comb comprising a case including an elongated bottom section and a lid therefor, a multiplicity of separate and independent teeth pivotally supported on a common axis in the bottom section and capable of being swung to lie within said bottom section, and also capable of being swung to extend from the bottom section and form a comb, and cooperating means between the lid and bottom section, whereby the teeth may be held rigidly in their extended position.

45 4. A comb comprising a case including an elongated bottom section, and a lid hinged to one edge thereof, a multiplicity of separate and independent teeth pivotally supported adjacent the other edge of the bottom section and capable of being swung inwardly to lie upon the bottom section, and permit the lid to enclose the same when in its closed position.

50 5. A comb comprising a case including an elongated bottom section, and a lid hinged to one edge thereof, a multiplicity of separate and independent teeth pivotally supported on a common axis adjacent the other edge of the bottom section and capable of being swung inwardly to lie upon the bottom

section, and also capable of being swung to extend from the associated edge of the bottom section and form a comb, and co-operative means carried by the bottom section and lid whereby the teeth may be clamped in their extended position. 70

6. A comb comprising a case including an elongated bottom section, and a lid hinged to one edge thereof, a multiplicity of teeth pivotally supported adjacent the other edge of the bottom section and capable of being swung inwardly to lie upon the bottom section and also capable of being swung to extend from the associated edge of the bottom section and form a comb, and opposing lips 80 or flanges carried by the bottom section and lid whereby the teeth may be clamped in their extended position.

7. A comb comprising a case including an elongated bottom section, and a lid hinged to one edge thereof, a multiplicity of teeth pivotally supported adjacent the other edge of the bottom section and capable of being swung inwardly to lie upon the bottom section and also capable of being swung to extend from the associated edge of the bottom section and form a comb, inwardly turned lips carried by the bottom section and lid whereby the teeth may be clamped against movement when in their extended position. 90

8. A comb comprising a case including an elongated bottom section, and a lid hinged to one edge thereof, a multiplicity of teeth pivotally supported adjacent the other edge of the bottom section and capable of being swung inwardly to lie upon the bottom section, and also capable of being swung to extend from the associated edge of the bottom section and form a comb, an inwardly turned lip formed upon the bottom section on which the teeth may rest when in their extended position, and a similar lip formed upon the free edge of the lid whereby the lid and bottom section may be used for clamping the teeth in their extended position. 100

9. A comb comprising a case including an elongated bottom section, a lid hinged to one edge thereof, a multiplicity of teeth pivotally supported adjacent the other edge of the bottom section and capable of being swung inwardly to lie upon the bottom section and also capable of being swung to extend from the associated edge of the bottom section and form a comb, an inwardly turned lip formed upon the bottom section on which the teeth may rest when in their extended position, a similar lip formed upon the free edge of the lid whereby the lid and bottom section may be used for clamping the teeth in their extended position, and teeth formed upon the 115 free edge of the lip on said lid for engaging said teeth. 120

10. A comb, comprising a case including an elongated bottom section, a lid section hinged to one edge thereof, a multiplicity of 130

separate and independent teeth pivotally supported adjacent the other edge of the bottom section, and spaced from each other, said teeth capable of being swung inwardly to lie on the bottom section, and also capable of being swung outwardly to extend from the case and form a comb, and cooperating means carried by the bottom and lid sections whereby the teeth may be clamped in their extended position.

11. A comb, comprising a case including a bottom section, a lid section hinged to the rear edge of the bottom section, said lid having an inwardly extending serrated flange at its free end, a multiplicity of separate and independent teeth pivotally supported adjacent the front edge of the bottom section and spaced apart from each other, said teeth capable of being swung inwardly to lie upon the bottom section, and also capable of being swung outwardly to extend from the case to form a comb, the serrations of the aforesaid flange defining teeth adapted to extend between the spaced apart comb teeth and clamp the same in their extended position.
